CLAIM

The ornamental design for a pet bottle, as shown and described.

DESCRIPTION

FIG. 1 is a front elevational view of a pet bottle; FIG. 2 is a rear elevational view thereof; FIG. 3 is a left side elevational view thereof; FIG. 4 is a right side elevational view thereof; FIG. 5 is a top plan view thereof; FIG. 6 is a bottom plan view thereof; and, FIG. 7 is a partial enlarged view of the selected portion 7 in FIG. 1.

The short broken lines in the figures are for the purpose of illustrating portions of the pet bottle that form no part of the claimed design. The long broken lines shown in FIGS. 1 and 7 define the bounds of the enlarged portion and form no part of the claimed design.
